HOODED VEST OR THE LIKE

Harry Kaufman, New York, N. Y.

Application March 19, 1957, Serial No. 45,323

Term of patent 14 years

(Cl. D3—4)

Fig. 1 is a front view of a hooded vest or the like showing my new design;

Fig. 2 is a rear view thereof;

Fig. 3 is another front view of the hooded vest as it appears with the hood in raised position; and

Fig. 4 is a rear view thereof.

I claim:

The ornamental design for a hooded vest or the like, substantially as shown.
